UNITED STATES PATENT OFFICE

151,287

DESIGN FOR A COMBINED DINING TABLE AND WRITING DESK

Margaret Sanders, Pittsburgh, Pa.

Application December 5, 1946, Serial No. 135,275.

Term of patent 3½ years

(Cl. D33—14)

To all whom it may concern:

Be it known that I, Margaret Sanders, a citizen of the United States, residing at Pittsburgh, in the county of Allegheny and State of Pennsylvania, have invented a new, original, and ornamental Design for a Combined Dining Table and Writing Desk, of which the following is a specification, reference being had to the accompanying drawing, forming part thereof.

Figure 1 is a perspective view of a combined dining table and writing desk, showing my new design with the extension leaves in their closed position; and

I claim:

The ornamental design for a combined dining table and writing desk, as shown.

MARGARET SANDERS.
